JUG

John T. Erickson, 15201 Yorkshire Lane, Huntington Beach, Calif., and Ronald W. Brown, 4114 E. 8th St., Long Beach, Calif.

Filed Apr. 13, 1965, Ser. No. 84,768

Term of patent 14 years

(Cl. D58—5)

FIG. 1 is a perspective view of a jug embodying our new design;

FIG. 2 is an elevational view;

FIG. 3 is an elevational view looking from the right of FIG. 2;

FIG. 4 is a top plan view;

FIG. 5 is a bottom plan view;

FIG. 6 is a sectional view taken on the line 6—6 of FIG. 2; and

FIG. 7 is a fragmentary enlarged sectional view taken on the line 7—7 of FIG. 1.

We claim:

The ornamental design for a jug, substantially as shown.
